CONCRETE COLUMN REINFORCEMENT JOINT

Bruno Bauer, Vienna, Austria

Application May 1, 1930, Serial No. 448,849
In Austria April 4, 1930

6 Claims. (Cl. 72—76)

This invention relates to improvements in securing the joint of superposed reinforcement skeletons for use in connection with ferro- or steel concrete columns. The joint is secured by 5 an independent member which I refer to hereinafter as a "special reenforcement" which is provided to secure the continuity of the hooping. The object of the arrangement of these special reinforcements is to prevent an interruption of 10 the hooping at the joint, the special reenforcement being used for reenforcement skeletons of any kind and shape, e. g. cast iron cores as well as longitudinal reenforcement bars or rods of any cross sectional area. The binding members may 15 consist either of a special wire hooping or of a pipe.

Some modes of carrying out the present invention are illustrated by way of example in the accompanying drawings, in which:—

20 Figure 1 is a substantially longitudinal sectional view of my improved reenforcement unit; Figure 2 is a substantially transverse sectional view of the same.

Fig. 3 is a perspective view of the invention on 25 an enlarged scale.

Figure 4 is a substantially longitudinal sectional view of a modification; Figure 5 is a substantially longitudinal transverse sectional view of the modification illustrated in Figure 4; and Figures 6 and 7 are perspective views thereof in different stages of assembly.

Referring to the drawings and particularly to Figures 1, 2 and 3, 1 denotes each of four spaced longitudinal reenforcement bars or rods which 35 are provided with distancing members 2 and eyes 3, the latter serving as means for holding inverted L-shaped joint guards 4 rigid on the rods 1. U-shaped brackets 5 are attached to the shorter arms of the guards 4 and embrace channel molds 9 transversely thereof. Embracing the bars 1 above and below the molds 9, respectively, are spiral reenforcing hooping members 6 and 7, the latter forming the top and bottom skeleton frames. Overlapping the abutting ends of the 40 hooping members 6 and 7 is a sleeve comprising a wire coil 8 which is large enough in diameter to not only embrace the ends of coils 6 and 7 but the upright portions of the guards 4 as well.

In the construction shown in Figures 4 to 7, 45 I support the molds 9 by means of a tubular distancing member 10 which is welded to the longitudinal reenforcement rods or bars 1 about the inner sides thereof. Connecting members 11 carried by and projecting radially of the tube 10, 50 support a tubular binding sleeve 12 which em-

braces the rods 1, as illustrated in Figure 5, and is spaced from the tube 10 to form a mold for the cement filling at the joint. Plate 14 supports from below, the beam-channels 9, the plate 14 being welded to the tubular binding sleeve 12 at 60 the lower end thereof.

The individual parts may be connected in any other convenient way for instance by screws, rivets and the like.

According to Figures 6 and 7 the rods 1 are held 65 in spaced relation by means of tubular sections 15, which are arranged on the inner sides of the rods and in practice, afford substantial reenforcement for the column.

Figures 6 and 7, show the manner in which the 70 column head is assembled at the floor or ceiling joint.

I claim:—

1. Reenforcement for concrete columns comprising superposed reenforcement skeletons, a 75 sleeve for the joint of abutting skeletons, a plate secured to said sleeve, a beam-channel fixed to said plate, a distancing tube within said sleeve and overlapping the said joint, and connecting members secured to said distancing tube and to 80 said sleeve.

2. In a reenforcing core for concrete columns, the combination of sections of spaced rods abutting each other at their ends to form a joint, inner sleeves disposed intermediate the sections and at 85 the joints of the rods, and an exterior sleeve embracing the rods and overlapping the latter at their joints.

3. In a construction of the character described, 90 vertical rods spaced from and connected to each other, supporting means secured to said rods, girders carried by said supports, embracing means for said rods between two succeeding supports, and further embracing means disposed at the points of connection of said girders on said rods, 95 said second embracing means being independent of said first embracing means to overbridge the space unembraced by the latter.

4. In a reenforcing core for concrete columns, 100 the combination of superimposed units consisting of spaced rods, adjacent ends of said units abutting each other to form joints, sleeves embracing the rods at the joints, and tubular sections intermediate the length of the rods and disposed interiorly of the core formed by the rods to reenforce the same between the joints.

5. In a reenforcing core for concrete columns, 105 the combination of superimposed units consisting of spaced rods adjacent ends of said units abutting each other to form joints, sleeves embracing 110

- the rods at the joints, and wire coils directly positioned upon and embracing the rods above and below the sleeves at the joints and separate wire coils overbridging the joints.
- 5 6. A skeleton for reenforcing concrete structure for tall buildings, comprising units of laterally spaced rigid bars, the ends of the bars of one unit abutting the ends of the bars of the next unit to form a joint, a sleeve embracing the bars at each joint, wire coils positioned upon and embracing the rods, said interconnected units of rigid bars forming one self-supporting unit extending 80 throughout the height of a building.
